(57) **CLAIM**

The ornamental design for a manual brake fluid bleeder, as shown and described.

DESCRIPTION

FIG. 1 is a perspective view of a body of manual brake fluid bleeder embodying our new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.
